CHILD RETAINER HAVING SOUNDING MEANS
Emile L. Bibeau and Muriel T. Bibeau, both of
5 Colony Way, Nashua, N.H. 03060
Filed May 3, 1966, Ser. No. 547,255
8 Claims. (Cl. 46—175)

This invention relates to child restraining or tethering devices, and more particularly to a child's tethering device of the type adapted to provide audible sounds responsive to the movement of a child secured to the device.

The main object of the invention is to provide a novel and improved child tethering device which is relatively simple in construction, which is arranged so that it may be used outdoors or indoors, which is attractive in appearance, and which is easy to set up for use.

A further object of the invention is to provide an improved child tethering device of the type provided with means to generate musical or other audible sounds responsive to the movement of a child tethered to the device, the device being inexpensive to manufacture, being durable in construction, being highly portable, and being arranged so that it may either be anchored to the ground for outdoor service or may be used indoors by being anchored to the floor beneath the caster of a piece of furniture.

Further objects and advantages of the invention will become apparent from the following description and claims, and from the accompanying drawing, wherein:

FIGURE 1 is a perspective view showing an improved child tethering device constructed in accordance with the present invention.

FIGURE 2 is an enlarged vertical cross-sectional view taken substantially on the line 2—2 of FIGURE 1.

FIGURE 3 is an enlarged vertical cross-sectional view taken transversely through an end portion of the tethering device of FIGURE 1 and showing the details of construction of the anchoring stake member employed with the device for anchoring same outdoors.

FIGURE 4 is a fragmentary elevational view taken substantially on the line 4—4 of FIGURE 3.

FIGURE 5 is a fragmentary vertical cross-sectional view taken through the lower portion of the stake assembly of FIGURE 3, but showing the pivoted spur arm thereof in retracted position.

FIGURE 6 is a fragmentary longitudinal vertical cross-sectional view taken through the end portion of the device of FIGURE 1, and illustrating the manner in which the caster of a piece of furniture is engaged in the recess provided therefor in the base portion of the tethering device.

Referring to the drawing, 11 generally designates an improved child tethering device constructed in accordance with the present invention. The device 11 comprises a supporting base 12 which may be of any suitable material, either rigid or flexible, and which is generally elongated in shape, the base being provided with a generally circular forward portion 13 which is somewhat enlarged relative to the remainder of the base. The rear portion of the base 12 is provided with an aperture 14 adapted to receive a ground-anchoring stake 15, presently to be described. The rear portion of the base is further provided with a recess 16 adapted to receive the caster 17 of an article of furniture 18, for anchoring the base against movement when the device is employed indoors. The stake 15 comprises a downwardly-tapering elongated shank portion 19 having the enlarged top head portion 20, the shank portion being formed with a substantially central bore 21 which merges with a recess 22 in the lower portion of the shank. Pivoted at 23 in said recess

2

is a spur arm 24 which is swingable outwardly and which is directed upwardly. A rod member 25 is slidably-engaged in the bore 21, the rod member having a tapered bottom end 26 which is wedgingly-engageable with the pivoted spur arm 24, said spur arm being deflected outwardly responsive to downward force exerted on the rod member 25. The rod member 25 is provided with the enlarged head 27 at its top end which limits the downward movement of the rod member in the bore 21. A short length of flexible cable 28 connects the top portion of the spur arm 24 and an upwardly-adjacent portion of the rod member 25, whereby the spur member 24 may be retracted to the position thereof shown in FIGURE 5 by pulling upwardly on the rod member 25, as where it is desired to withdraw the stake 15 from the ground to disengage same from the flat base 12.

When the device 11 is to be anchored to the ground, the stake 15 is engaged through the aperture 14 and is driven into the ground, the rod member 25 being finally pushed downwardly by exerting force on its top head 27 to swing the spur arm 24 outwardly so as to provide additional anchoring effect and so as to prevent the stake 15 from being loosened or easily dislodged from its anchoring position. When it is desired to unfasten the device from the ground, the rod member 25 is pulled upwardly by grasping its enlarged top head 27 and exerting upward force, whereby the flexible cable element 28 pulls the spur arm 24 inwardly into the recess 22 substantially to the position of FIGURE 5, allowing the stake 15 to thereafter be easily pulled out of the ground.

Secured substantially concentrically on the enlarged circular portion 13 of base 12 is an upwardly-convex generally hemispherical pedestal element 30 having a central top boss 31 in which is journaled a vertical swivel pin 32, the bottom end of the swivel pin being provided with a cotter pin 33, or similar retaining means, to prevent withdrawal of the swivel pin 32 from the boss 31. The upper portion of the swivel pin 32 is enlarged, as shown at 34, and secured thereon is a generally spherical body 35 forming a part of a toy figure 36, the body 35 being hollow and being secured at its upper portion to an upwardly convergent neck portion 37 depending from a generally spherical simulated head 38 which is, in turn, integrally-formed with the upwardly-convergent, generally conical simulated cap 39. The various elements 35, 37, 38 and 39 are hollow, and the whole body 36 may be molded from suitable flexible material, such as rubber, or the like.

Mounted in the conical cap 39 is a conventional bulb whistle or reed device 40 adapted to emit a whistling noise responsive to squeezing of the hollow flexible upper portion comprising the neck 37, the head 38, and the cap 39 of the toy body 36.

The generally spherical body portion 35 is formed with a horizontally-extending tubular chamber 42 opening at the front side of the toy body 36. Integrally-molded in the portion 35 substantially coaxially with the tubular chamber 42 is an elongated bulb 43 which extends from the rear wall of portion 35 toward the open front end of the chamber 42 and which is provided with a conventional bulb whistle 44 of the reed type, or any other suitable type. Designated at 47 is a coil spring which surrounds the elongated bulb 43 and which has its rear end turn 48 secured to the rear wall of the spherical body portion 35. Secured to the front end turn of the coil spring 47 is a generally circular rigid cap 49 which normally seats on the annular rim defined at the front end of the tubular chamber 42, being biased to seating position thereon by the force of the coil spring 47. Thus, the rim of the tubular chamber 42 limits the inward retraction of the cap 49. The cap 49 is extensible forwardly, for example, as shown in dotted view in FIG-

URE 2, whereupon the coil spring 47 contracts in diameter, exerting squeezing pressure on the bulb 43. When the bulb 43 is squeezed, it causes the whistle 44 to generate a musical tone or to whistle, similar to the manner in which the bulb whistle member 40 emits a whistling sound when the top portion of the toy figure is squeezed.

A flexible tether strap 50 is connected by a length of flexible cable 51 to the center of the cap 49, whereby an infant may be secured to the cable by means of the conventional fastening strap 50. As will be readily apparent, when an infant is thus secured to the device, movement of the infant away from the toy body 36 causes the spring 47 to be extended, for example, as shown in dotted view in FIGURE 2, whereupon the bulb 43 is squeezed by the contraction of the turns of the spring, causing the whistle 44 to generate a musical tone, the intensity thereof depending upon the rapidity of movement of the infant or child. Since the toy body 36 is freely rotatable on the pedestal 30, the child may move in any desired direction, the inward and outward movements of the child causing the spring 47 to be extended and retracted, thereby causing the bulb 43 to be alternately squeezed and released, which causes the whistle 44 to intermittently generate whistling tones.

As above-described, the device may be employed either outdoors by employing the anchoring stake 15, or may be used indoors, in which case the base 12 is anchored by engaging a furniture caster 17 in the recess 16, as above-described.

While a specific embodiment of an improved child tethering device has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A child tethering device comprising a supporting base, means to anchor said base against movement, an upstanding hollow toy figure mounted on said base, a bulb whistle device mounted in the figure, said whistle device including a flexible bulb, extensible and contractile fastening means surrounding said bulb and secured to the figure at its inner end and having a free outer end, said fastening means contracting to exert squeezing pressure on the bulb responsive to longitudinal extension of

the outer free end of the fastening means, a tether means adapted to be secured to a child, and means connecting said tether means to the outer free end of said fastening means.

5. 2. The child tethering device of claim 1, and wherein the hollow toy figure is swivelly-mounted on the base.

3. The child tethering device of claim 1, and wherein said extensible and contractile fastening means comprises a coil spring surrounding said bulb.

10 4. The child tethering device of claim 3, and a cap secured to the outer end of the spring and being engageable with the figure to limit inward movement thereof.

5. The child tethering device of claim 3, and wherein said anchor means comprises a stake engageable through 15 a portion of the base and having a pivoted outwardly-swingable upwardly-directed bottom spur arm and means to deflect said spur arm outwardly after the stake has been driven into the ground.

6. The child tethering device of claim 5, and wherein 20 said stake has a longitudinal bore extending from the top end of the stake to said spur arm and wherein said deflecting means comprises a rod element slidably-mounted in the bore and extending above the top end of the stake, the bottom end of the rod element being wedgely-engageable with said spur arm.

7. The child tethering device of claim 6, and flexible 25 cable means connecting said spur arm to the rod element, whereby the spur arm can be retracted from an outwardly-swinged anchoring position by pulling the rod element upwardly.

8. The child tethering device of claim 1, and wherein 30 said extensible and contractile fastening means comprises a coil spring surrounding said bulb and wherein said supporting base comprises a relatively flat plate-like body, 35 said body being provided with a recess for at times receiving said caster wheel of an article of furniture, for anchoring the base against movement.
